UNITED STATES PATENT OFFICE.

THOMAS KIRKWOOD, OF CHICAGO, ILLINOIS.

GRATE FOR FURNACES.

SPECIFICATION forming part of Letters Patent No. 390,376, dated October 2, 1889.

Application filed May 14, 1886. Serial No. 202,190. (No model.)

To all whom it may concern:

Be it known that I, THOMAS KIRKWOOD, a citizen of the United States, residing at Chicago, Illinois, have invented certain new and 5 useful Improvements in Grates for Furnaces, of which the following is a specification.

In the drawings, Figure 1 is a plan view of my grate. Fig. 2 is a plan view of one of the finger-bars with a number of grate-fingers on 10 the bar ready to be pushed up into place. Fig. 3 is a vertical section taken longitudinally of the grate-bar at one of the end sections, showing the means of connecting the finger bar with the end sections.

15 In the drawings, A represents the fingers of the grate; B, the finger-bar; C, the frame or side pieces supporting the finger-bars; D, the trunnions at the ends of the finger-bar, and E, the rocking bar.

20 In making my improved grate, I take a suitable frame of cast or other proper iron and of the size of the furnace into which the grate is to be placed. I provide along the sides of this grate-frame bearings, preferably inclined, into 25 which the trunnions supporting the finger-bars rest and move when in position and while being rocked. I make these finger-bars preferably of wrought-iron and of a length suitable to reach from side to side of the grate-frame.

30 The grate-fingers are made in sections, so that they can be placed in position on the finger-bar one at a time and slid up against each other into position. This enables me to remove any

particular section of the grate-fingers should it become warped or worn out in use and replace it with new ones. The end section of the grate-fingers is preferably provided with a socket or bearing, into which the ends of the finger-bars are inserted, as shown in Figs. 2 and 3. This socket should be of a square form 35 or such other shape that the finger-bars would be rigidly attached to the end sections of the grate-fingers when in place, so that such end sections and finger-bars would rock together. I preferably make the end sections of 40 a size to support two grate-fingers, as shown in Fig. 2 of the drawings. I also provide them with trunnions D to fit into the bearings on the side of the grate-frame. As all these features will be apparent from an inspection of 45 the drawings, I do not consider that they need be described with greater minuteness of detail. 50

What I regard as new, and desire to secure by Letters Patent, is—

The combination, in a shaking-grate, of finger-bars, and grate-fingers mounted or supported thereon, the grate-fingers being made in sections and the end sections being severally provided with a trunnion resting in bearings in the grate-frame, and with a socket in 55 6, which one end of the finger-bar is inserted and supported, substantially as described.

THOMAS KIRKWOOD.
